UNITED STATES PATENT OFFICE.

JAMES S. WILSON, OF SCRANTON, PENNSYLVANIA.

SECTIONAL GRATE BAR.

Application filed October 17, 1922. Serial No. 595,102.

To all whom it may concern:

Be it known that I, JAMES S. WILSON, citizen of the United States, residing at Scranton, in the county of Lackawanna and 5 State of Pennsylvania, have invented certain new and useful Improvements in Sectional Grate Bars, of which the following is a specification.

This invention relates to improvements in 10 grate structures and more particularly to a furnace grate for employment where soft coal is the fuel used. Ordinarily grates employed under these conditions comprise a number of grate bars which are arranged 15 within the fire box of the furnace. It is desirable to employ, in lieu of such bars, a number of sections supported upon bearing bars and adapted to be independently removed when repairs become necessary. 20 However, it has heretofore been found impracticable to employ grates of the sectional type where soft coal was burned, for the reason that in the combustion of the fuel fusion takes place to a certain extent and 25 a fused mass is formed which flows downwardly through the draft openings in the grate surface and, upon reaching the under side of the grate where the temperature is lower, becomes hardened and caked. To 30 permit the passage of air through the grate it is necessary to remove these fused accumulations, but where it has been attempted to employ the ordinary constructions of sectional grates, under these conditions, it has 35 been found that in ramming the poker between the fused accumulations and the top surface of the grate to dislodge the accumulations, the sections are extremely liable to become displaced with a consequent loss 40 of time and fuel. Therefore, it is the primary object of the present invention to provide a sectional grate of the stationary type especially designed for use where soft coal is employed as a fuel, means being 45 provided for preventing displacement of the grate sections under the conditions mentioned above, without, however, in any way interfering with the ready and convenient removal of any one or more of the sections 50 in the event repairs or replacements become necessary.

More specifically it is an important object of the present invention, to provide, in combination with a bearing bar of a specific 55 structure, grate sections supported thereon in assembled relation and embodying means

adapted to coact with elements of the said bar to lock the sections to the bar and prevent their displacement when ramming away the fused accumulations, and in this connection the invention contemplates so constructing the locking means that while it will perform its function in the most efficient manner, it will not in any way interfere with removal of any one or more of the sections and such removal may be accomplished without the loosening or other manipulation of extraneous fastening means.

In the accompanying drawings:

Figure 1 is a side elevation of the grate 70 structure embodying the present invention;

Figure 2 is a top plan view thereof;

Figure 3 is a detail vertical longitudinal sectional view on the line 3—3 of Figure 2;

Figure 4 is a vertical transverse sectional 75 view on the line 4—4 of Figure 3;

Figure 5 is a similar view on the line 5—5 of Figure 3;

Figure 6 is a perspective view of one end 80 of one of the sections;

Figure 7 is a similar view of the other end of the said section.

The grate sections embodying the invention are indicated in general by the numeral 1 and these sections are assembled and supported upon bearing bars which are indicated by the numeral 2. While these bearing bars are capable of employment in supporting grate sections of various constructions differing from the grate sections disclosed herein, they serve, in the particular combination, a new purpose which will presently be made clear. Each of the bearing bars 2 is cast integral throughout and comprises spaced side members 3 which may be given the form illustrated more particularly in Figure 1 of the drawings, or may be given any other form desired. These side members 3 are connected at their ends by cross pieces 4 which are, as stated, integral with 100 the said side members, and the side members are further connected by integral cross pieces 6 extending in a series throughout their lengths and located close to their upper edges. The bearing bar is to be supported in the usual manner within the frame of the grate structure and of course any desired number of the bars will be employed and they may be arranged in a single group or in a number of groups, as may be desired.

The grate sections 1 are of counterpart

form and construction and each is in the nature of an integral casting. Each section comprises side members 7, intermediate longitudinal bars 8, connecting end portions 9 and 10, and an intermediate bridge portion 11, all of these parts being as stated cast integral, and the side members and bars 8 being so spaced as to provide longitudinal air passages 12 of the required area opening vertically through the supporting surface of the section, it being evident by reference to the drawings that the upper edges of the sides 7, bars 8, end pieces 9 and 10, and bridge piece 11, all occupy a common plane and constitute the supporting surface of the section.

The locking means for preventing displacement of the sections preferably comprises a depending boss 13 cast integral between the middle two of the series of bars 8 and located near the end 9 of the section. This boss is formed preferably with a rounded or arcuate lower edge indicated by the numeral 14, and with a seating recess 15 which opens, by way of a throat 16, through the said edge, the recess and throat likewise opening through the opposite side faces of the said boss. As illustrated most clearly in Figure 3 of the drawings the side walls of the throat 16, which walls are indicated by the numeral 17, are slightly converged in an upward direction and as the throat is somewhat narrower than the recess 15, locking lugs 18 are provided at the opposite sides of the said throat, the upper side of each of these lugs providing a downwardly inclined shoulder 19. The throat 16 is of a width just sufficiently greater than the greatest transverse dimension of the bridge pieces 6, to permit the opposing ends of the lugs 18 to pass the bridge piece as the section is disposed upon or removed from the bearing bar. In other words, the throat is of a width to provide sufficient clearance to enable the bridge piece 6 to enter the recess 15 through the said throat, and it will likewise be observed by reference to Figure 3 that the distance between the top wall of the recess 15 and the shoulders 19 is slightly greater than the thickness of the bridge piece 6 so that the bridge piece will be freely accommodated within the recess. By reference to Figure 5 it will be evident that when the sections are disposed upon the bearing bars, they will rest upon the upper edges of the side members of the bearing bar in properly centered relation, and with the bridge pieces 6 received within the recesses 15 of the several sections. The recess 15 of each section being of greater width than the throat 16, and therefore of greater width than the transverse dimension of the bridge piece 6 received therein, the section may have bodily shifting movement upon the bearing bar longitudinally thereof. Of course, in mount-

ing the section upon the bearing bar it will be so positioned that the throat 16 will be immediately above the bridge piece 6 which is to be engaged, and the section may then be lowered into position resting upon the bar. Likewise removal of the section may be readily accomplished by shifting it in one direction or the other the requisite short distance to bring the throat 16 immediately beneath the said bridge piece 6, whereupon the section may be bodily lifted from the bar. However, the lugs 18 are so positioned that the shoulders 19 thereof may engage beneath the bridge piece 6, and it therefore follows that in the ramming of the accumulations from the top surface of the sections, the sections will be displaced longitudinally of the bar a fraction of an inch but sufficiently to engage one or the other of the shoulders 19 beneath the respective bridge pieces 6. Upon such engagement the end of the section at which the boss 13 is provided, will, of course, be securely locked to the bearing bar and prevented from being upwardly displaced.

In order that the other end of each section may be similarly locked under the conditions noted, means is provided which will now be described. The numeral 20 indicates lugs which preferably have beveled or inclined under faces 21 and which are formed integral upon the end piece 9 of each section, being located at the opposite sides of the longitudinal middle of the section. Locking lips 22 are similarly formed upon the end piece 10 of each section and are so positioned that when two of the sections are assembled end to end upon the bearing bar, the lips 22 of one section will engage beneath the lugs 20 of the adjacent section. Inasmuch as that end of the last-mentioned section which carries the lug 20, is locked to the bearing bar through engagement of one or another of its lugs 18 beneath the bridge piece 6, and this end of the said second-mentioned section is thereby prevented from lifting from the bar, the engagement of the lips 22 beneath the lugs 20, will, of course, prevent the meeting end of the first-mentioned or companion section from lifting from the bar. It therefore follows that when all of the sections have been arranged in properly assembled relation upon the bearing bar they will all be locked against upward displacement especially under the conditions referred to above, although any one of the sections may be readily removed by centering its throat 16 with relation to the engaged bridge piece 6, lifting its end 9 to clear the lugs 18 from the bridge piece, and then slipping the lips 22 out from engagement beneath the lugs 20 upon the companion section, and by a reversal of these operations, the same section or a replacement section may be installed.

In order to provide for a proper proportioning of the air space between the adjacent ends of companion sections, the end piece 9 of each section 1 is preferably formed with 5 bosses 23 located outwardly beyond the lugs 20, and the opposite end 10 of each section is formed midway between the lips 22 with a boss 24.

In order to properly relatively space the 10 sections upon adjacent bearing bars, the sides 7 of each section are formed upon their outer faces with spacing lugs or bosses 25, and the bosses upon the two side members of each section are arranged in the staggered relation shown in Figure 2 of the 15 drawings.

Having thus described the invention, what is claimed as new is:

1. In a stationary grate, in combination, 20 a bearing bar having an anchoring element, a grate section disposed upon the bar and normally stationary but having limited movement longitudinally of the bar, the said section having spaced locking elements 25 near one end engageable beneath the anchoring element, and means at the ends of the grate section normally preventing upward displacement of the grate section from the bearing bar.

2. In a stationary grate, in combination, 30 a bearing bar having transverse bridge pieces, and a grate section disposed upon the bearing bar and resting upon said bridge pieces, the grate section having a depending 35 boss near one end formed with a recess and with locking elements at the open side of the recess, said boss being engaged around one bridge piece and the dimensions of the recess being somewhat greater than the dimensions of the bridge piece and the distance 40 between the locking elements being only slightly greater than the width of the bridge piece whereby the grate section may have limited movement longitudinally of 45 the bearing bar and will normally be prevented from moving upwardly.

3. In a stationary grate, in combination, 50 a bearing bar having spaced side members and transverse bridge pieces between the side members, a plurality of grate sections disposed upon the bar, a depending boss upon each section near one end thereof having a recess receiving one of the bridge pieces and provided upon the opposite walls thereof with locking elements engageable beneath the bridge piece whereby the sections may have limited longitudinal movement but will normally be prevented from upward displacement, means at the ends of the

sections for maintaining them in spaced relation, and means at the ends of the sections to hold them against upward displacement.

4. In a stationary grate, in combination, 60 a bearing bar having anchoring elements, 65 grate sections disposed upon the bar and having limited movement longitudinally thereof, the sections at their meeting ends having mutually engaging means preventing upward displacement of one section relative to the other section, and means adjacent one end of each section for coaction with an anchoring element of the bearing bar to restrain the said end of the section from upward displacement.

5. In a stationary grate, in combination, 70 a bearing bar having an anchoring element, 75 grate sections disposed upon the bar, the said sections at their meeting ends being provided one with a lug and the other with a locking lip engageable beneath the lug, 80 means upon the section having the locking lip adjacent the other end thereof for locking engagement with the anchoring element of the bearing bar, and means for maintaining the ends of the sections in spaced 85 relation and permitting limited endwise movement of the sections.

6. In a stationary grate, in combination, 90 a bearing bar having anchoring elements, 95 grate sections disposed upon the bar and each provided adjacent one end with means engageable with an anchoring element to restrain the said end of the section from upward displacement and on its opposite end with laterally spaced lips engaging under 100 correspondingly spaced lugs on the meeting end of an aligned section, the ends of the sections being otherwise out of contact, and spaced abutments on the ends of the sections permitting limited endwise movement 105 thereof.

7. In a stationary grate, in combination, 110 a bearing bar, a plurality of grate sections disposed thereon, coacting locking means upon the bearing bar and one end portion 115 of each section for preventing upward displacement of the said end of the section, means on the sections to prevent upward displacement of the ends thereof remote from said coacting locking means, and means on the ends of the sections to maintain them in spaced relation and permit limited endwise movement thereof whereby each section may be removed independently of all the other sections.

In testimony whereof I affix my signature.

JAMES S. WILSON. [L. s.]
